CLAIM

The ornamental design for a basketball hoop as shown and described.

DESCRIPTION

FIG. 1 is a perspective view of a basketball hoop showing the claimed design in an environment of use;

FIG. 2 is a perspective view of the basketball hoop in a partially exploded environment;

FIG. 3 is a perspective view of the basketball hoop;

FIG. 4 is a left-side elevation view of the basketball hoop, wherein a right-side elevation view thereof is a mirror image of the left side elevation view;

FIG. 5 is a front elevation view thereof;

FIG. 6 is a rear elevation view thereof;

FIG. 7 is a top plan view thereof; and,

FIG. 8 is a bottom plan view thereof.

Broken lines in the figures illustrate portions of the basketball hoop that form no part of the claimed design.

1 Claim, 8 Drawing Sheets
